LEON NAUDET, OF PARIS, FRANCE.

APPARATUS FOR THE CONTINUOUS CARBONATION OF ALKALINE SUGAR-JUICE.

SPECIFICATION forming part of Letters Patent No. 739,702, dated September 22, 1903.

Application filed November 8, 1902. Serial No. 130,498. (No model.)

To all whom it may concern:

Be it known that I, LEON NAUDET, a citizen of the Republic of France, residing at Paris, France, have invented certain new and useful Improvements in Apparatus for the Continuous Carbonation of Alkaline Sugar-Juice, of which the following is a specification.

In French Patent No. 295,906, dated January 5, 1900, and granted to Emile Duplos and Edmund Duplos and Leon Naudet, of Paris, France, there is described a process of and apparatus for the continuous carbonation of alkaline sugar-juice.

My present invention relates to an improvement in such apparatus by reason of which the operation of the device is modified and simplified and, further, to the combination, with the carbonation vessel, of a device which has for its object to initially determine and regulate the degree of alkalinity of the carbonated juice delivered from the apparatus.

It is now well understood that the vertical space which a definite quantity of carbonated sugar-juice will occupy in the carbonation vessel will depend upon its alkalinity, or, in other words, that the viscosity of the carbonated juice will decrease as the alkalinity of the sugar-juice is neutralized by the action of the acid gas employed. Consequently if means are provided which may be adjusted to determine the level at which the carbonated sugar-juice shall leave the apparatus the degree of alkalinity of the carbonated sugar-juice can be initially determined.

The accompanying drawings will serve to illustrate my invention and in which similar numerals indicate like parts.

Figure 1 is a side elevation and partial section through a pair of carbonating vessels and the devices for fixing the level at which the carbonated sugar-juice shall leave the apparatus. Fig. 2 is a plan view taken on the line X X of Fig. 1. Fig. 3 is an enlarged view, taken at right angles to the view shown in Fig. 1, of the device for regulating the level at which the carbonated sugar-juice shall leave the apparatus. Fig. 4 is an enlarged view of the mechanism employed for regulating the admission of the alkaline sugar-juice to the carbonation vessel. Fig. 5 is an enlarged view of the mechanism for controlling the valve regulating the admission of the al-

kaline sugar-juice to the carbonation vessel. Fig. 6 is an enlarged view of the bottom of the carbonation vessel.

In the drawings, 10 indicates a carbonation or treating vessel, which may be of any suitable size. The top of the vessel is provided with a ventilator 11, through which any excess of acid gas (preferably carbonic-acid gas) may find egress from the vessel; 12, a pipe through which the alkaline sugar-juice (hot or cold and preferably made alkaline with lime) is introduced and discharged into the bottom of the carbonation vessel. Surrounding this pipe is a perforated conical screen 13, and connected to the top of this screen, through a suitable coupling 14, is a pipe 15, through which the acid gas is introduced into the tank under pressure. Arranged above the perforated screen 13 is a horizontal screen 16. The screens 13 and 16 serve, by checking the upward flow of the sugar-juice and gas, to promote an intimate mixture of these bodies, and, further, to prevent frothy matters and scum from rising through the body of the sugar-juice above the screens. In the bottom of the carbonation vessel is a valved outlet 17, through which any deposit or heavy matters may be drawn off.

18 indicates a pipe, through which the carbonated sugar-juice may be drawn from the carbonation vessel. The upper end of this pipe is protected by a shield 19, which serves to prevent bodies in the form of lumps, scum, &c., from entering the pipe 18. The pipe 18 is carried downward in the carbonation vessel and then outward through its wall and upward and connected with the interior of the tank 20 at its bottom. Situated within 90 and carried through the tank 20 is a pipe 21, which serves as a discharge or outlet pipe for the carbonated sugar-juice. The upper end of this pipe is provided with extensions 22, in which are formed slots 23, and situated 95 within this pipe is a short pipe 24, arranged horizontally, onto the upper end of which are bolts 25, adapted to move and be secured in the slots 23 of the extensions 22. It will be seen that by vertically adjusting the pipe 24 in the pipe 21 the level of the outlet for the carbonated sugar-juice above the bottom of the carbonation vessel 10 and tank 20 can be varied as desired.

26 indicates a test-pipe connected to the bottom of the tank 20.

Situated to the left of the carbonation vessel 10 is a cylindrical vessel 27, connected at its bottom to the carbonation vessel 10 through a pipe 28. Connected to the lower part of the pipe 28 is a test-pipe 29. Located within the vessel 27 is a float 30, which is connected to a stem 31, adapted to reciprocate vertically in the guides 32, secured to the side of the carbonation-tank. Pivotal connected to the upper end of the stem 31 is a link 33, the lower end of which is pivotally connected to a lever 34, secured on shaft 35, on which is the valve 36, which controls the supply of alkaline sugar-juice to the carbonation vessel. The link 33 has in its upper and lower ends a series of holes 37 in order that its point of connection through the bolts 38 with the stem 31 and lever 34 may be altered, and thereby vary the initial position of the valve 36, and thus regulate the inflow of alkaline sugar-juice and the movement of the valve under the action of the float 30. Secured to shaft 35 is a lever 39. This lever is slotted at 40, which slot incloses the stem 31 between the stops 41. The lever 39 serves as a means for manually acting upon the stem 31 to actuate the valve 36 when desired.

30 The operation of my device is as follows: A definite quantity of alkaline sugar-juice and acid gas is introduced into the bottom of the carbonation vessel 10 through the pipes 12 and 15, and after a short time the alkalinity of the resultant sugar-juice is determined by any suitable device. If the alkalinity of the sugar-juice is found to be that which is desired, the top of the pipe 24 in the tank 20 is secured at the then level of the carbonated sugar-juice in the carbonation vessel 10. If, however, the alkalinity is found to be less than that required, more alkaline sugar-juice is introduced until the required alkalinity is obtained. After having determined 45 the level for the required alkalinity the valve 36 in pipe 12 is adjusted to permit a definite quantity of alkaline sugar-juice to flow into the carbonation vessel in a unit of time, which alkaline sugar-juice will displace a corresponding quantity of carbonated sugar-juice, which will flow through pipe 18 into tank 20 and thence through pipe 24 out of the apparatus. This condition will prevail so long as the required alkalinity of the carbonated 50 sugar-juice is maintained, for it will be readily seen that the level of the carbonated sugar-juice in the carbonation vessel and tank will remain practically constant so long as the alkalinity and viscosity of the carbonated sugar-juice are constant. Should, however, a condition prevail which would result in a change of alkalinity—as, for instance, should the sugar-juice contain more or less alkali than is normally present or the pressure of the 55 acid gas be increased or decreased, &c.—then a change in the level of the sugar-juice in the

carbonation vessel will take place and through the float 30 a change in the position of the valve 36 controlling the supply of alkaline sugar-juice to the carbonation vessel. Bearing in mind now that the level of the carbonated sugar-juice in the carbonation vessel corresponds to its alkalinity and viscosity, it will be seen that when the alkalinity of the carbonated sugar-juice is increased above 75 the normal it is necessary to cut off or decrease the ingress into the carbonation vessel of further alkaline sugar-juice until the acid gas has acted upon the sugar-juice in the carbonation vessel to restore the normal alkalinity and level. On the other hand, should the alkalinity decrease it will be necessary to introduce further alkaline sugar-juice to create the desired balance.

In the drawings, Fig. 1, the level occupied 85 by the pipes 24 in contiguous tanks 20 is shown to be different. This illustration was made for the purpose of showing, first, that the position of the pipe 24 is capable of adjustment, and, second, to bring out the fact 90 that two contiguous tanks can be adjusted when supplied with sugar-juice of different degrees of alkalinity to produce a sugar-juice of the same degree of alkalinity. It will be observed that the test-pipe 26 is connected to 95 both of the tanks 20. This test-pipe draws from both tanks, and manifestly a sample drawn from it could be tested in comparison with that drawn from either of the pipes 21.

Having thus described my invention, what 100 I claim, and desire to secure by Letters Patent, is—

1. An apparatus for the treatment of alkaline sugar-juice comprising in its construction, a treating vessel, a pipe through which alkaline sugar-juice is introduced into the vessel, a pipe through which an acid gas is introduced into the vessel, means for controlling the ingress of the alkaline sugar-juice, and means for regulating the level of the discharge of the treated sugar-juice.

2. An apparatus for the treatment of alkaline sugar-juice, comprising in its construction a treating vessel, a pipe through which alkaline sugar-juice is introduced into the vessel, a pipe through which an acid gas is introduced into the vessel, means governed by the level of the carbonated sugar-juice in the vessel, for controlling the ingress of the alkaline sugar-juice, and means for regulating the 120 level of the discharge of the treated sugar-juice.

3. An apparatus for the treatment of alkaline sugar-juice, comprising in its construction a treating vessel, a pipe through which alkaline sugar-juice is introduced into the bottom of the vessel, a pipe through which an acid gas is introduced into the bottom of the vessel, a screen surrounding the outlet of said pipes, a second screen arranged horizontally 130 in the treating vessel above the outlet of said pipes, means for controlling the ingress of

alkaline sugar-juice, and means for regulating the level of the discharge of the treated sugar-juice.

4. An apparatus for the treatment of alkaline sugar-juice, comprising in its construction, a treating vessel, pipes through which alkaline sugar-juice and an acid gas are respectively introduced into the vessel, means governed by the level of the treated sugar-juice in the vessel for controlling the ingress of the alkaline sugar-juice, a tank arranged external to the vessel, a pipe connecting the interior of the treating vessel with the tank, and means located in the tank for controlling the level of discharge of the treated sugar-juice.

5. An apparatus for the treatment of alkaline sugar-juice, comprising in its construction, a treating vessel, a pipe through which alkaline juice is introduced into the vessel, a pipe through which acid gas is introduced into the vessel, a pipe of larger diameter than the pipe through which the alkaline juice is introduced, for conducting the carbonated juice from the vessel, means for controlling the ingress of the alkaline sugar-juice, and means for regulating the level of the discharge of the treated sugar-juice.

6. An apparatus for the treatment of alkaline sugar-juice, comprising in its construction a treating vessel, a pipe through which an alkaline juice is introduced into the vessel, a supplemental tank, a U-shaped pipe of larger diameter than that through which the

alkaline juice is introduced into the treating vessel interposed between the interior of 35 the treating vessel and the tank, means for controlling the ingress of the alkaline sugar-juice, and means for regulating the level of the discharge of the treated sugar-juice.

7. In combination with the treating vessel 40 and the mechanism for controlling the flow of the alkaline sugar-juice into said vessel, of a supplemental tank, a pipe connecting said tank with the interior of the treating vessel, a discharge-pipe connected to said tank, and 45 means for altering the level of the top of the discharge-pipe.

8. In an apparatus of the class described, the combination with the treating vessel, of a device for initially determining the degree of 50 alkalinity of the material treated in and discharged from said vessel.

9. An apparatus for the treatment of alkaline sugar-juice, comprising in its construction a treating vessel, a supplemental tank, 55 means for connecting said treating vessel and tank together, and means in the tank for controlling the level of the fluid-body introduced into the treating vessel.

In testimony whereof I affix my signature 60 in the presence of two witnesses.
